UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed August 4, 1927. Serial No. 210,484.

This invention relates to rigid all-steel car roofs of the riveted-up type wherein self-supporting roof sheets extend from side plate to side plate of the car and are rigidly secured together along their adjacent side margins by hollow upstanding weatherproofing seams which function as roof supporting carlines.

The principal object of the present invention is to increase the strength and rigidity of the above type of roof by strengthening and stiffening the roof seams in the region of the ridge. Another object is to increase the weatherproofing qualities of the seam at the ridge. Other objects are simplicity and cheapness of construction, fewness of parts, ease of assembly and compactness of design. The invention consists principally in providing the hollow upstanding seams with reinforcing and stiffening members which are secured within said seams on opposite sides of the ridge and terminate short of the eaves. It also consists in providing the running board saddles with flanges for weatherproofing the joints between the lapped seam flanges at the ridge; and it also consists in the parts and in the arrangements and combinations of parts hereinafter described and claimed.

In the accompanying drawing, which forms part of this specification and wherein like symbols refer to like parts wherever they occur,

Fig. 1 is a plan view of a portion of the car roof embodying my invention;

Fig. 2 is a transverse section through the roof between seams on the line 2-2 in Fig. 1;

Fig. 3 is an enlarged transverse section through the ridge portion of the roof, the section being taken along the line 3-3 in Fig. 1;

Fig. 4 is a vertical cross-section through the seam at the ridge on the line 4-4 in Fig. 3; and

Fig. 5 is a similar cross-section through the seam, the section being taken through one of the seam stiffeners on the line 5-5 in Fig. 3.

Referring to the accompanying drawing, my invention is shown in connection with an all-steel, single course car roof comprising Z-bar side plates 6, which are arranged with their ribs horizontally with their inner

flanges projecting upwardly. Heavy gage metal roof sheets 7, extend transversely of the car from side plate to side plate and are provided with depending eaves flanges 8 which overhang and are riveted or otherwise secured to the outer faces of the upstanding inner flanges of the side plates. The roof sheets 7, which are pressed from blanks of uniform width, slope downwardly on opposite sides of the ridge to form a hip or arcuate roof, and are provided along their adjacent side margins with raised ribs A which are lapped and rigidly secured together to form hollow upstanding seams which function as carlines. As shown in the drawing, each of these side marginal ribs A comprises a flange or web portion 9 which extends upwardly from the body of the sheet and has at the top thereof a flat flange or portion 10 that extends outwardly or laterally with relation to the body of the sheet. The web portion 9 of each side marginal rib A gradually diminishes in height towards the eaves; and the surplus metal gained thereby is turned down at outer edge of the horizontal flange portion 10 of said rib in the form of a depending flange 11. This causes the ribs A, which are of inverted L-shaped section at the ridge, to gradually assume an inverted channel-shaped section on opposite sides of the ridge. As the web portions 9 of the lapped ribs A diminish in depth towards the eaves, there is a corresponding increase in the depth of the depending flanges 11 thereof towards the eaves.

At the eaves ends of the sheets, the lapped ribs A are curved downwardly and merge into the plane of the body of the sheets where said sheets are turned down to form the depending eaves flanges 8; and the lateral flanges 12 that appear at the eaves ends of said lapped ribs are the surplus of metal resulting from the downwardly curved eaves end portions thereof, which metal is turned outwardly to form said lateral flanges 12.

As shown in the drawing, the roof is braced and stiffened at the angle between roof sheets of the side plates by means of angle-shaped brackets 13 located beneath the eaves end portions of the hollow upstanding roof seams or carlines. The angle brackets 13 are arranged with one flange vertical and rigidly secured flatwise of the inner face of

the upstanding inner flanges of the side plates and with the other flange projecting inwardly below the seams and rigidly secured on opposite sides thereof to the body 5 portions of the roof sheets by rivets which extend through the outstanding lateral flanges 12 thereof.

Running boards 14 extend longitudinally of the car at the ridge and rest on and are 10 bolted to the upwardly off-set outer marginal portions of the top flanges of angle shaped running board saddles 15, which flanges rest on and are riveted or otherwise rigidly secured to the tops of the hollow 15 upstanding roof seams. The other flanges 16 of the angle-shaped running board saddles project downwardly, and the saddles are positioned over the seams so that the depending flanges 16 thereof overhang the 20 joints between the lapped top flanges 10 of the ribs A which form said seams and thus serve to weatherproof said joints.

Additional strength and rigidity are imparted to the roof by a metal reinforcing or 25 stiffening member 17 located within each seam on each side of the ridge. As shown in the drawing, the reinforcing and stiffening members 17 are of substantially inverted 30 channel-shaped section and extend longitudinally of the seam and snugly fit within the hollow upstanding roof seam. The inverted channel-shaped reinforcing and stiffening members 17 have their web portions rigidly secured flatwise to the top flanges 35 of the lapped ribs A of each seam by the rivets which secure said rib together. The two stiffeners and reinforcing strips 17 in each seam are preferably spaced apart on opposite sides of the ridge and are arranged 40 with their adjacent ridge end portions disposed beneath and rigidly secured to the outer end portions of the running board saddles 15 by the securing rivets therefor. The two seam stiffeners for each seam extend far 45 enough beyond the ends of the running board saddles to secure the desired stiffness for the roof seams between the ridge and eaves. By the arrangement described, the seam stiffeners 17 and running board saddles 50 15 are rigidly secured to each other and to the hollow seams and thus serve to greatly increase the load carrying capacity of the roof by strengthening and stiffening the ridge portions of said hollow roof seams 55 against bending or buckling under vertical load. It is noted that the depending flanges 16 of the running board saddles serve to weatherproof the ridge portions of the seams which comprise mere overlapping 60 flanges.

The hereinbefore described arrangement is applicable to roofs having side plates and

seams of various cross-sections, and I do not wish to be limited to the exact side plate and seam construction shown and described. 65

What I claim is:

1. A car roof comprising load sustaining roof sheets connected by rigid seams, running board saddles rigidly secured to said seams, and stiffening means secured to said 70 seams between the ridge and eaves of the car and to the ends of said running board saddles whereby said stiffening means co-operate with said running board saddles to strengthen and stiffen the ridge portion of 75 the roof.

2. A car roof comprising load sustaining roof sheets connected by rigid seams, running board saddles rigidly secured to said 80 seams, and seam stiffeners rigidly secured to said seams between the ridge and eaves of the car with their ridge end portions rigidly secured to the adjacent end portions of said running board saddles.

3. A car roof comprising load sustaining 85 roof sheets connected by rigid seams, running board saddles rigidly secured to said seams, and flanged seam stiffeners extending longitudinally on each seam on opposite 90 sides of the ridge and rigidly secured to said seam, said flanged seam stiffeners having their adjacent ridge end portions disposed beneath and rigidly secured to the ends of the running board saddles and their outer 95 end portions terminating beyond the ends of said saddles.

4. A car roof comprising load sustaining roof sheets connected by hollow upstanding 100 seams that function as carlines, running board saddles rigidly secured to said seams, and reinforcing strips located within and rigidly secured to each of said hollow 105 seams, said seam stiffeners being located between the ridge and eaves of the car with their adjacent ridge ends extending beneath and rigidly secured to the ends of said running board saddles.

5. A car roof comprising self sustaining 110 roof sheets which extend from eaves to their side margins by hollow upstanding 115 seams whose ridge section comprises overlapping inverted L-shaped flanges at the side margins of adjacent sheets, and metal running board saddles resting on and rigidly 120 secured to said overlapped seam flanges at the ridge, said running board saddles being provided with depending flanges which extend substantially the full length of said saddles and overhang the outer edges of the overlapping seam flange of each seam.

Signed at New Kensington, Pennsylvania, this 29th day of July, 1927.

CHARLES DAVID BONSALL.
